UNITED STATES PATENT OFFICE.

GEORGE H. KLINGLER AND WILLIAM H. KLINGLER, OF EMLENTON, PENNSYLVANIA,
ASSIGNORS OF ONE-HALF TO WRIGHT WIRE COMPANY, OF WORCESTER, MASSA-
CHUSETTS, A CORPORATION OF MASSACHUSETTS.

MARLINESPIKE.

1,121,927.

Specification of Letters Patent. Patented Dec. 22, 1914.

Application filed April 22, 1912. Serial No. 692,475.

To all whom it may concern:

Be it known that we, GEORGE H. KLINGLER and WILLIAM H. KLINGLER, both citizens of the United States, residing at Emlenton, in the county of Venango and State of Pennsylvania, have invented a new and useful Improvement in Marlinespikes, of which the following is a specification, accompanied by drawings forming a part of the same.

10 The object of our invention is to provide a marlinespike which is more convenient than those in common use, and to enable one hand to be employed in inserting the spike in a cable and the other hand for imparting a rotative movement thereto.

Referring to the accompanying drawings, Figure 1 shows a side elevation of a marline-spike embodying our present invention. Fig. 2 is a side elevation showing the spike rotated on its longitudinal axis one quarter turn from the position shown in Fig. 1.

Similar reference characters refer to similar parts in the different figures.

Referring to the drawings, 1 denotes a handle having an enlarged end 2 adapted to receive a pressure from the palm of the hand in order to force the point 3 of the spike between the strands of a cable. Between the handle 1 and the point 3 the spike is flattened throughout nearly its entire length, as

shown at 4, and also slightly increased in width, producing between the blade and the point 3 a tapered section 5. At the base of the handle is a laterally extended arm 6.

In using the spike the point 3 is inserted 35 between the splices of the cable until the latter are separated by the blade 4 by pressure applied to the enlarged end 2 of the handle. The tool is then rotated a partial turn by means of the radially extended arm 6, in order to separate the strands and produce an 40 opening through which other strands may be drawn in splicing the cable.

We claim,

A marline spike including a handle having an enlarged end, a flattened blade section in alignment with said handle and having a tapered end terminating in a point, and a rigid arm extending laterally from said spike between the end of said handle 50 and the flattened blade section and lying substantially in the plane of the latter at right angles to the axis of said spike.

Dated this first day of April, 1912.

GEORGE H. KLINGLER.
WILLIAM H. KLINGLER.
